UNITED STATES PATENT OFFICE.

HOWARD G. LOCKE, OF WEYMOUTH, MASSACHUSETTS, ASSIGNOR TO THE BROCKTON LAST CO., OF BROCKTON, MASSACHUSETTS.

LAST.

SPECIFICATION forming part of Letters Patent No. 559,492, dated May 5, 1896.

Application filed August 9, 1894. Serial No. 519,874. (No model.)

To all whom it may concern:

Be it known that I, HOWARD G. LOCKE, a citizen of the United States, residing at Weymouth, in the county of Norfolk and State of Massachusetts, have invented certain new and useful Improvements in Lasts, of which the following is a full, clear, and exact description, reference being had to the accompanying drawings, making part of this specification, in which--

Figure 1 is a top view of my improved last. Fig. 2 is a side elevation of the same. Fig. 3 is a vertical section through the center of the same. Fig. 4 is a transverse vertical section on the line 4 4 of Fig. 3.

My invention relates to that class of lasts which are divided transversely into two sections, one movable upon the other, and has for its object to improve the construction, whereby the last can be more readily withdrawn from the boot or shoe without liability of tearing or injuring the same; and to this end my invention consists in certain novel features and details of construction, as hereinafter set forth and specifically claimed.

In the said drawings, A represents the fore-part section of the last, and B the heel-section. At the rear end of the fore-part section is formed an inwardly-curved seat or socket b, extending from 5 to 6 and occupying the lower portion of said rear end, as shown in Figs. 2 and 3. The front face c of the heel-section is curved outwardly to correspond to and fit the inwardly-curved seat b at the rear end of the fore-part section. The fore-part section is provided with a tongue d, projecting horizontally outward therefrom, said tongue, which is preferably composed of a metal plate secured in place by bolts e e, extending into a vertical slot f in the heel-section, which is adapted to receive said tongue d, the latter being provided at its outer end with a hole to receive a pivot-pin g, which passes through the front end of the heel-section at or near the center of its height and serves to connect the two sections A B together in such manner that they will have a firm bearing on each other at the joint when the last is in its normal position, the heel-section being adapted to be swung upward

around said pivot-pin into the position shown in dotted lines in Figs. 2 and 3 to permit of the convenient removal of the last from the boot or shoe within which it is placed.

The vertical slot f in the heel-section B is 55 provided with a socket composed of two metal plates h h, riveted to a bottom piece i, Figs. 3 and 4, which forms a stop for the tongue d to strike against when the heel-section is brought down into its operative position, so 60 that its bottom will register with the bottom of the fore-part section, and when the heel-section of the last is swung upward into the position shown in dotted lines, Figs. 2 and 3, the outer corner 10 of the shoulder k is 65 brought into contact with the straight face 12, which forms the upper part of the fore-part section, which thus forms a stop to limit the upward movement of the heel-section, and it will be seen that when the heel-section 70 is thus swung upward its front end does not project above the "comb" or upper corner 20 of the fore-part section, thus avoiding any liability of the upper of the shoe being pressed out of shape or injured from this cause. 75

By thus pivoting the heel-section, as above described, upon the end of a tongue projecting out horizontally from the fore-part section, so that said heel-section will swing around within the seat b at the rear end of 80 the fore-part section on the pivot-pin g without rising or sliding up at its front end on the fore-part section, it will be obvious that it will move in the arc of a much smaller circle, and consequently as it is swung upward its 85 rear end will be drawn inward and raised above the counter of the shoe within which it is placed much more rapidly, whereby the operation of withdrawing the last from the boot or shoe is greatly facilitated and the liability of tearing or injuring the upper thus prevented. 90

I am aware that transversely-divided lasts have been constructed in which the fore-part section and heel-section have been pivoted 95 or hinged together in such manner that the heel-section could be swung upward on the fore-part section. Hence I make no broad claim to such construction. In none of these lasts, however, as far as I have been able to 100

ascertain, has the heel-section been pivoted to a tongue projecting rearwardly from the fore-part section, whereby the heel-section is caused to merely swing around at its front 5 end on its pivot-pin within a seat at the rear end of the fore-part section without rising or sliding up on the rear face of the said fore-part section, which I consider the essential feature of my invention, as it causes the rear 10 end of the heel-section to swing upward in the arc of a much smaller circle and consequently be drawn inward to shorten the last much more rapidly to relieve the same and facilitate its withdrawal from the shoe.

15 What I claim as my invention, and desire to secure by Letters Patent, is—

1. A transversely-divided last, consisting of a fore-part section having at its rear end an inwardly-curved seat or socket occupying 20 a portion of said rear end, and a heel-section provided with a vertical slot and having at its front end an outwardly-curved seat adapted to fit and turn within the inwardly-curved seat of the fore-part section, said heel-section 25 being pivoted near its front end, by means of a pin passing therethrough, on a tongue projecting rearwardly from the fore-part section into the slot of the heel-section, whereby said heel-section is adapted to turn on its pivot

within the seat or socket of the fore-part section, substantially as set forth. 30

2. In a last transversely divided into two sections, the combination of the fore-part section having at its rear end an inwardly-curved seat or socket occupying a portion of 35 said rear end, the heel-section provided with a vertical slot and having an outwardly-curved seat at its front end adapted to fit and turn within the curved seat of the fore-part section, a tongue immovably secured to and 40 projecting rearwardly from the fore-part section and fitting within the slot of the heel-section, and a pivot-pin passing horizontally through the heel-section near its front end at about the center of its height and through 45 said tongue, whereby the front end of the heel-section is adapted to turn on said pivot within the socket or seat of the fore-part section, and a suitable stop for limiting the downward movement of the heel-section, substantially 50 as set forth.

Witness my hand this 1st day of August,
A. D. 1894.

HOWARD G. LOCKE.

In presence of—

P. E. TESCHEMACHER,
WILLIAM WRIGHT.
